Atty.

UNITED STATES PATENT OFFICE.

FREDERICK EISSNER, OF NEW YORK, N. Y.

SURGICAL NEEDLE AND HOLDER.

SPECIFICATION forming part of Letters Patent No. 472,258, dated April 5, 1892..

Application filed August 29, 1891. Serial No. 404,090. (No model.)

To all whom it may concern:

Be it known that I, FREDERICK EISSNER, of the city, county, and State of New York, have invented a new and useful Surgical Needle and Holder; and I do hereby declare that the following is a full and exact description thereof, reference being had to the accompanying drawings, and to the letters of reference marked thereon, making a part of this specification.

My invention relates particularly to the class of devices known as "suture-needles," in which the needle proper is carried at the end of a handle or holder of convenient length, which may also carry a supply of thread; and it has for its object to improve the construction of such devices, so that the needle proper may be more fully under the control of the operator, may be held fast in the holder or released therefrom by manipulation at the outer end of the holder, and may be used either fast to the holder or loosely held thereby, as desired, and so that the end of the holder may be smooth and free from projecting set-screws and the like.

In the drawings, Figure 1 is an elevation of one embodiment of my invention. Fig. 2 is a central section thereof, and Fig. 3 is a sectional detail view thereof on the line $\alpha\alpha$ of Fig. 1 on a plane at right angles to the plane of Fig. 2.

The sleeve or hollow shaft A, which constitutes the holder for the needle, is preferably provided at one end with a head a, which is perforated in different directions by holes b and b', adapted to receive the shaft of the needle C. Within the hollow of the sleeve or cylinder A is a clamping-rod B, furnished at its lower end with a screw-thread d, engaging with a corresponding screw-thread in the sleeve A, and also furnished with a head f, having a milled edge. The end of the clamping-rod B is adapted to bear against the shaft of the needle C when the latter is placed in the hole b or b', and by rotating said shaft by means of the head f the needle may be released or held firmly in position.

An enlarged cylinder D is carried on the shaft A and contains a bobbin H on the shaft A for holding thread. The cylinder D is also provided with a slot, as J, through which the thread is run. A cap E fits over the enlarged

cylinder D and is itself held in place by the head f and the rod B, which passes through it.

The needle C is provided with a perforated 55 guide-piece G for the thread, fixed thereon near one end, which carries the thread along the shaft A and needle C, keeping it out of the way of the operator, and which also operates as a shoulder or guard to prevent the 60 shank of the needle from slipping through the hole b when placed in position. The holes b b' being substantially diametrical and the head a being perforated by any number of such holes that may be found convenient and 65 desirable, the needle can be placed in a number of different positions with reference to the axis of the shaft A, as indicated in the drawings both by full and dotted lines.

In operation the needle is placed in one of 70 the holes adapted to receive it, using the hole which will hold the needle in the position most desirable with reference to the work to be done, and the needle is fixed and held firmly in position by turning the head f. The 75 thread is run through the slot J, the guide G, and the eye of the needle, and the apparatus is ready for use. In some cases the needle may be used without being clamped, the guide-piece G serving to hold the needle in place 80 while being pushed through the parts to be sewed.

The whole device is simple in construction and can be taken apart readily for cleaning after use. Whenever desired, the position of 85 the needle with reference to the shank of the holder can be changed without withdrawing the needle from the suture by rotating the clamping-rod. The perforated guide-piece on the needle not only permits the needle to be 90 used without being clamped by the rod, but will hold the thread in place should the holder be freed from the needle for the purpose of changing the position of the latter. There are no set-screws projecting from the end of 95 the needle-holder to interfere with the free use of the needle or to prevent the proper and thorough cleansing of the instrument.

I claim as my invention—

1. A surgical needle having an eye near its 100 point and a perforated shoulder and guide on its shank, substantially as shown and described.

2. In combination, a needle, a shoulder-piece

secured thereon, and a shaft perforated to receive the shank of said needle, substantially as shown and described.

3. In combination, a needle, a perforated guide-piece secured thereon, and a shaft or holder having a head perforated at different angles to the axis of said shaft, with holes adapted to receive the shank of said needle, substantially as shown and described.

4. In combination, a hollow shaft perforated to receive a needle, and a rod fitting

loosely within said shaft and furnished with a screw-thread engaging with a screw-thread in said shaft and adapted to bear upon said needle, substantially as shown and described. 15

In testimony whereof I have signed my name to this specification in the presence of two subscribing witnesses.

FREDERICK EISSNER.
